UNITED STATES PATENT OFFICE.

GEORGE AINSWORTH, OF GREAT NECK, NEW YORK, ASSIGNOR TO BEVERLY LIGHTS CORPORATION, OF PROVIDENCE, RHODE ISLAND, A CORPORATION OF RHODE ISLAND.

DESIGN FOR A BODY SHELL FOR LIGHTING FIXTURES.

Application filed September 22, 1922. Serial No. 3,796. Term of patent 14 years.

To all whom it may concern:

Be it known that I, GEORGE AINSWORTH, a citizen of the United States, and resident of Great Neck, in the county of Nassau and State of New York, have invented a new, original, and ornamental Design for a Body Shell for Lighting Fixtures, of which the following is a specification, reference being had to the accompanying drawing, forming part thereof.

The figure is a direct elevation of a body shell for lighting fixtures showing my new design.

I claim—

The ornamental design for a body shell for lighting fixtures as shown.

GEORGE AINSWORTH.
